(57) CLAIM

The ornamental design for a pickup truck rear bucket storage single drawer, as shown and described.

DESCRIPTION

FIG. 1 is a perspective front view of a pickup truck rear bucket storage single drawer showing my new design;

FIG. 2 is a perspective back view thereof;

FIG. 3 is a front view thereof;

FIG. 4 is a back view thereof;

FIG. 5 is a right-side view thereof;

FIG. 6 is a left-side view thereof;

FIG. 7 is a top view thereof;

FIG. 8 is a bottom view thereof;

FIG. 9 is a magnified view of a top portion of the front side thereof;

FIG. 10 is a magnified view of a middle portion of the front side thereof;

FIG. 11 is a magnified view of a middle portion of the back side thereof; and,

FIG. 12 is a magnified view of a bottom portion of the back side thereof.
